UNITED STATES PATENT OFFICE

2,120,195

CONCRETE SLAB HOUSE CONSTRUCTION

Carl Valenti, Pittsburgh, Pa.

Application September 2, 1937, Serial No. 162,204

6 Claims. (Cl. 72—19)

This invention relates to the construction of houses or other buildings primarily adapted to use slabs of concrete or the like in the construction of the walls thereof, whether the interior or exterior side walls, the ceiling or the floor.

It is particularly aimed to provide novel means whereby the slabs may be readily connected to the joists, studs, beams or other structural elements and be of such a nature that all of the material or parts necessary may be made in the factory and delivered to the job or place of use, especially to erect small, economical houses with air-spaced and insulated walls, floor, ceiling and roof.

15 It is also aimed to provide such structure wherein the slabs and associated parts may be used in applying the slabs to houses or buildings already built.

The more specific objects and advantages will 20 become apparent from a consideration of the description following taken in connection with accompanying drawings illustrating an operative embodiment.

In said drawings:—

25 Figure 1 is a fragmentary vertical sectional view through a house or building embodying my improvements;

Figure 2 is a horizontal sectional view taken on the plane of line 2—2 of Figure 1;

30 Figure 3 is a vertical sectional view taken on the plane of line 3—3 of Figure 1;

Figure 4 is an enlarged vertical sectional view of portions of slabs forming the inner side wall of the building and associated parts;

35 Figure 5 is a detail perspective view of a side wall slab attaching bracket;

Figure 6 is a detail perspective view of a ceiling suspending clip;

Figure 7 is a view similar to Figure 4 showing 40 a modified form of attaching bracket;

Figure 8 is a vertical section taken on the line 8—8 of Figure 7;

Figure 9 is a vertical sectional view showing 45 a modified form of ceiling slab attaching means;

Figure 10 is a vertical sectional view showing a modified form of attaching means for the outside wall slabs;

Figure 11 is a vertical sectional view through 50 a modified form of means for attaching ceiling slabs;

Figure 12 is a horizontal section taken on the line 12—12 of Figure 11;

Figure 13 is a vertical section of a further 55 modified form for attaching ceiling slabs;

Figure 14 is a vertical section through a modified form of ceiling and side wall joints, and Figure 15 is a horizontal section taken on the line 15—15 of Figure 14.

Referring specifically to the drawings wherein 5 like reference characters designate like or similar parts, a house or other building is but fragmentarily shown, embodying parts of inner and outer side walls and ceiling but it is to be understood that the same principles may be practiced 10 in the construction of the floor, roof, and other walls or parts. Specifically, the side of the building frame comprises fabricated metallic I beams as at 10 and for the support of the ceiling, has concrete or other beams or joists as at 11. 15

The outside walls may consist of slabs 12 of 20 concrete or the like which are interlocked as at 13 with the aid of mortar, any other sealing medium or the like and the exterior of which slabs after they have been applied may be finished with stucco or any other suitable material. Bolted to the beams 10 as at 14 are attaching 25 brackets 15 for the slabs. Such brackets are shown specifically in Figure 5. They have attaching portions or walls 16, forwardly extending 25 walls 17 and 18 from which rise in spaced relation, lower and upper hook flanges 19 and 20 respectively. Said slabs 12 have hooks 21 engageable over the hooks 19 and 20, and such hooks 21 have attaching portions 22 embedded in the 30 material of the slabs.

It will be realized that in the construction described, the slabs 12 may be readily attached by engaging the hooks 21 with the flanges 19 and 20, following which the joints at 13 are pointed 35 up, having previously had an application of concrete, mortar or other sealing medium applied thereto, and following which, the exterior may be finished with stucco or any other desired way. If desired, spacing battens 23 may be interposed 40 between the slabs 12 and the beams 10, preferably fastened to the latter.

The interior wall may consist of a series of 45 slabs 24 preferably of the same material as those at 12 and which are joined along concavo-convex 50 surfaces at 25, with mortar or a sealing medium interposed. Such slabs have hooks 26 with ends embedded therein and which hooks 26 are detachably engaged with adjacent flanges 19 and 20 of the brackets 15 adjacent to the same, and 50 fastened like the other brackets, by bolts 14 to the beams 10. It will be realized that these slabs 24 may be readily applied to the adjacent brackets 15 and the joints as at 25 effectively closed or sealed. 55

At the ceiling, the wall preferably consists of a series of slabs 27 of the same material and shape and with the same joints as the slabs 24. Marginal slabs or rows may be supported from an adjacent concrete beam or joist 11 through the engagement of hooks 28 thereon with projections 29 anchored in the beam.

Brackets, loops or clips 31, as detailed in Figure 6, have terminals 32 anchored or embedded in certain of the joists 11 and they are overlapped by free terminals of hooks 30, preferably from opposite sides, anchored in the slabs 27, the slabs 27 thus being suspended from the joist 11.

15 In lieu of the concrete or cementitious joists 11, metallic joists or I beams may be employed as at 33, in Figure 14 and by means of rivets 34, plates 35 are secured to such joists or beams. The adjacent slab 27 has a fastening 38 embedded therein provided with a head at 38' which is adapted to pass through a T-shaped slot 36 of the plate 35 and then rest thereon to support the adjacent portion of the ceiling.

As shown in Figure 9, where a joist 11' of metal 25 is used in place of that at 11, a modified form of the loop or bracket 31 is provided at 39 in the form of U-bolt having its legs passing through flanges of the joist 11' and secured thereto by nuts 41 threaded on the legs 40.

30 The bracket 15, rather than being permanently fastened or bolted in place may be detachably applied as by means of an enlarged slot 42, having an enlarged entrance opening 43 by means of which the bracket, here designated 15', may be engaged over a head of a bolt 44 on the beam 10, and supported by such bolt. This form of bracket 15' may be used for either slabs 12 or 24 as preferred.

In Figure 10, a modified form of bracket is 40 used for the support of the slabs 12, the same being designated 45 and bolted as at 46 to a stud or beam 10. This bracket 45 has parallel portions 47 offsetting oppositely extending flanges 48 which are detachably engageable by the hooks 21.

In lieu of the suspension of the ceiling slabs 27 from the elements 31, they may be suspended from brackets 49, of the same shape as used at 45, the same having attaching portions 50 and 50 L-shaped slots 51 engaged by bolts or screws 52 fastened to cement joists 11a. The heads 52 of such bolts are passed through slots 51 and the brackets thereafter rest on such heads. Said brackets have U-shaped portions at 53 from which 55 hook flanges 54 extend in opposite directions and are engageable by hook members 55 embedded at 56 in slabs 27' identical with those at 27.

Figure 13 illustrates the ceiling slab supported from a metal beam or joist 11b in lieu of the 60 joist 11a. In this form, the bolt 53' correspond-

ing to that at 53 is connected to one of the flanges of the beam 11b. Otherwise the structure is identical with that of Figures 11 and 12.

Particular attention is called to the fact that the hooks of the different forms are employed 5 at adjacent edges of adjacent slabs and engage the same or a common bracket, thereby insuring that the joints between the edges of the slabs will be smooth and flush.

Various changes may be resorted to provided 10 they fall within the spirit and scope of the invention.

I claim as my invention:—

1. In building construction, structural means having an attaching bracket, terminal attaching 15 portions on said bracket disposed in the same plane, slabs, said slabs each having means engaging one of said portions, the joint of said slabs being between said means.

2. In building construction, structural means 20 having an attaching bracket, terminal attaching portions on said bracket disposed in the same plane, slabs, said slabs each having means engaging one of said portions, the joint of said slabs being between said means, said slabs being inter- 25 engaged at the joint and the last mentioned means being hooks.

3. In building construction, structural means having a bar-like member forming an attaching bracket, terminal attaching portions on said 30 bracket, slabs, said slabs each having means engaging one of said portions, the joint of said slabs being between said means, said bracket having an offset attaching portion, and hooks in a common plane offset from the plane of attach- 35 ment.

4. In building construction, structural means having a bar-like member forming an attaching bracket, terminal attaching portions on said 40 brackets, slabs, said slabs each having means engaging one of said portions, the joint of said slabs being between said means, said bracket having an offset attaching portion, and hooks in a common plane offset from the plane of attachment, 45 said hooks being spaced apart and extending in the same direction.

5. In building construction, structural means having an attaching bracket, attaching portions on said bracket, slabs, said slabs adjacent a joint each having means engaging one of said portions, 50 said bracket having an attaching portion, and hooks in a common plane offset from the plane of attachment, said hooks extending in opposite directions.

6. Building construction according to claim 3 55 wherein the structural element has a headed member, said offset attaching portion having a slot provided with an enlargement to facilitate engagement with the headed member.

CARL VALENTI. 60
